SEWING MACHINE BOBBIN

George R. Eckhardt, Cliffwood, N.J., assignor to Coats & Clark Inc., New York, N.Y., a corporation of Delaware

Filed July 3, 1958, Ser. No. 746,467

5 Claims. (Cl. 242—169)

The present invention has to do with sewing machine bobbins and the manufacture thereof. It relates particularly to a bobbin which comprises a central tube and two parallel side walls attached to said tube. Such bobbins may be made of metal, plastic or paper.

The present invention contemplates the use of paper because it is cheap and readily worked to accommodate itself to the method described herein.

The type of bobbin which is herein described is usually purchased with the thread mass wound thereon and after removal of the thread the bobbin itself is discarded. Of necessity such bobbins must be very low priced. This type of bobbin is commonly used by manufacturers of garments and the like where it is uneconomical to rewind a bobbin because of the time spent in so doing.

It is desirable with commercial high speed machines to have a bobbin made of light weight material so that when the thread is drawn off the bobbin very rapidly the bobbin does not overrun and cause the thread to tangle in the bobbin case.

It is also desirable to have the side walls of the bobbin stiff enough so that they do not separate much at the periphery from the thread mass and arranged so that the thread may not readily jam between the thread mass and the inside of the bobbin walls.

It is also desirable to have a bobbin which when wound with thread maintains its original dimensions and does not expand or change its dimensions as time elapses.

It is also desirable to arrange the bobbin so that it will rotate freely within the bobbin case of the sewing machine and so that the peripheral edges of the bobbin walls are in the optimum position in relation to the exit from the bobbin case.

All of these desired results and advantages are obtained with the present invention as will be more fully described hereinafter.

The following is a description of my invention, reference being had to the drawings, in which:

Fig. 1 is a perspective view of a short piece of paper tube with a thread mass wound thereon and a pair of wall blanks for the bobbin walls;

Fig. 2 is a longitudinal section of a pair of dies and a supporting spindle and the various elements which go to make up the loaded bobbin;

Fig. 3 is a sectional view like Fig. 2 but taken after the dies have been brought together to assemble the various elements of the bobbin;

Fig. 4 is a plan view of the finished bobbin;

Fig. 5 is a side view of the finished bobbin; and

Fig. 6 is a detailed side view of part of the bobbin showing a strand of thread adjacent to a side wall of the bobbin.

Looking at Fig. 1, T shows a thread mass wound on a hollow paper tube 1 in the more or less diagonal direction used in winding such bobbins (a universal wind). It will be noted that the tube 1 on which the thread mass T is wound is somewhat longer than the thickness of the thread mass. This permits the wall blanks 2 and 3 to

2

be placed over the ends of the tube 1 and the tube and wall blanks locked together, as will be hereinafter described.

In assembling the walls on the tube, shaping the same and compressing the thread mass, a pair of dies, such as those shown in Figs. 2 and 3, are used. The upper die member is shown at 5, the lower die member at 6. The faces of dies 5 and 6 are furnished with radially disposed corrugations, those on die 5 are shown at 7 and those on die 6 at 8. Each die is also furnished with a central bushing, the surface of which is specifically designed to lock the walls of the bobbin and the tube together. The bushing for die member 5 is shown at 9 and the bushing for die member 6 at 10. A central spindle 11 is designed to pass freely but snugly through the central bore of the bobbin blank and the bushings 9 and 10 of the dies. This spindle serves to center the blank and prevents collapse of the tube 1 during the compression of the bobbin blank and thread mass.

In the operation of the die mechanism, the bobbin elements shown in Fig. 1, that is, the tube 1 with the thread mass T thereon, and the tube wall blanks 2 and 3 are assembled on the spindle 11 as shown in Fig. 2. The dies are then moved toward each other to the position shown in Fig. 3. During this operation the tube 1 is compressed longitudinally to a small extent as shown in Fig. 3 and the ends of the tube are turned over and locked into engagement with the outside surfaces of the walls of the bobbin as shown in these figures. These turned-over portions of the tube 1 are shown at 12. During this operation the thread mass is compressed and radial corrugations are formed on the walls 2 and 3 of the bobbin, which corrugations, as shown in Fig. 5, are formed on both sides of the bobbin and are impressed 35 into the thread mass 2.

It is desirable that these corrugations be reasonably deep and pronounced. However, there is a limit to the pressure which may be imposed on the thread without injuring it and it is desirable that the raised surfaces on one wall are disposed opposite to the depressed surfaces on the opposite wall so that the thickness of the thread mass remains constant. "Raised" as used herein means away from a central plane disposed between and parallel to the side walls of the bobbin. "Depressed" means the opposite, i.e., toward such a central plane. A portion of a surface is considered "raised" with respect to another "depressed" portion when it lies farther from such a central plane than the latter portion. The corrugations may take some other shape or disposition than radial, but it is desirable that they exist on both sides of each wall, as shown in the figure. This result can be readily obtained with relatively thin paper bobbin side walls. As shown in Fig. 6 the edge view of the corrugated wall 3 may be of a wavelike or undulating form when developed. This smooth curve allows proper pressure on the thread mass with less danger of cutting or straining the thread than might be the case if sharper corrugations were impressed.

Upon separation of the dies 5 and 6 and the raising of the spindle 11, the finished bobbin can be readily removed from the dies.

It is desirable to heat the die members because they will more readily shape the elements of the bobbin and the thread mass and the finished article will hold its dimensions and shape better if compressed under heat. The dies may be heated by electric resistance elements or by circulating heated liquid therethrough. These features are not shown because their structure is no part of this invention. A temperature of about 250° F. has been found advantageous with a paper bobbin and any conventional sewing thread wound on it.

A bobbin made in accordance with the method herein

disclosed has a number of advantages. It is economical because it may be made of paper. It is so constructed that it is relatively strong with the walls firmly locked to the tube. It carries maximum length of thread because the thread mass is compressed. It is economical to make because the assembly of the bobbin, compression of the thread mass and the formation of the corrugations on the walls of the bobbin are all performed in one operation.

The corrugated side walls of the bobbin are advantageous for a number of reasons. They, of course, strengthen and stiffen the walls so as to minimize the spreading apart of the walls and the separation of the walls from the thread mass. In conjunction with the projecting ends of the tube they permit ready rotation of the bobbin in the bobbin case without sticking. The free and smooth unwinding of the thread is an important feature in high speed machines. Because the raised areas on one wall are opposite to the depressed areas on the opposite wall, the thread mass is evenly compressed and there are no high and low points of compression in the thread mass especially around the periphery thereof which is the case if the raised points of one wall are opposite to the raised points of the other wall. This permits of a higher average compression without injury to the thread.

It is also true when the respective corrugations are arranged, as shown in Fig. 5, that there is less tendency for the thread mass and walls to separate so that there is less chance in case of a backlash of the thread finding its way down between the thread mass and the walls to jam and cause breakage. This feature is illustrated in Fig. 6 where a strand of thread 20 is shown overlying the protuberances 22 with the thread mass at T and one of the side walls of the bobbin at 3. It will be seen that if the thread finds its way over to the side wall 3, with a tendency to go down between the thread mass T and the wall 3 into gap 21, it is prevented from doing so by protuberances 22 on the thread mass which follow closely the corrugations in the wall 3. This improved result follows from the fact that the raised point on one wall is opposite the depressed point on the other and the thickness of the thread mass is constant. When the corrugations in the respective walls are arranged otherwise, the thread mass is apt to be more highly compressed between the depressed corrugations and less compressed between the raised corrugations and, of course, the high pressure will tend to cause the depressed portions of the thread mass to "snap back" more than the raised portions, thus reducing the depth of the corrugations.

It is probably also true that when the thread mass is compressed in a corrugated bobbin of the kind disclosed and when the thread mass is wound in the conventional diagonal manner shown in Figs. 1 and 5 there is an internal shifting of the various layers in the thread mass, one in relation to the other, which brings about a frictional resistance to a return to the original condition of the thread mass which in turn means that the thread mass is more inclined to retain the shape and form impressed upon it by dies of the character shown in Figs. 2 and 3. If the corrugations on the two walls were disposed other than as shown herein, that is, if the depressed portions in the two walls were opposite to each other and the raised portions opposite to each other, this internal shifting and creating of friction between the layers is not present, at least not to a marked extent, and there is a greater tendency for the thread mass to expand and at-

tempt to go back to the condition it was in before being compressed by the dies.

The deeper corrugations and the relation of those on one wall to the other bring about a more desirable bobbin 5 which is stiffer, less apt to tangle and which rotates freely and easily within the bobbin case.

Although but a specific embodiment of the invention is herein shown and described, it will be understood that numerous details of the construction shown may be altered or omitted without departing from the spirit of the invention as defined by the following claims.

What is claimed is:

1. In a sewing machine bobbin having a central tube connecting two annular side walls and wound with a 15 thread mass having side surfaces opposed to said side walls, an improvement comprising raised and depressed areas of the side walls, each raised area of one side wall lying opposite a depressed area of the other side wall and the side surfaces of the thread mass conformed to the 20 raised and depressed areas of the side walls.

2. A wound sewing machine bobbin as described in 25 claim 1 in which a protrusion on the side surface of the compressed thread mass enters far enough into each raised area of the side walls so that a thread stretched between the two adjacent depressed areas of the same side wall 30 overlies the protrusion.

3. In a sewing machine bobbin having a central tube connecting two annular side walls and wound with a 35 thread mass having side surfaces opposed to said side walls, an improvement comprising corrugations in the side surfaces so proportioned and distributed that the distance through the thread mass from one side surface to the other, measured in a direction parallel to the axis of central tube, is the same for all points on the side surfaces 40 which are equidistant from the axis of the central tube and corrugations in the side walls conformed to those in the side surfaces.

4. In a sewing machine bobbin having a central tube 45 of paper connecting two annular paper side walls and wound with a thread mass having side surfaces opposed to said side walls, an improvement comprising radially extending raised and depressed areas of the side walls, the raised area of one side wall lying opposite a depressed area of the other side wall, the side surfaces of the thread 50 mass conformed to the raised and depressed areas of the side walls, and in which a protrusion on the side surface of the thread mass enters far enough into each raised area of the side walls so that a thread stretched between the two adjacent depressed areas of the same side wall overlies the protrusion.

5. The sewing machine bobbin of claim 4 in which the developed edges of the side walls have wavelike form.
